(57) **CLAIM**

The ornamental design for a mounting plate for a ski binding, as shown and described.

DESCRIPTION

FIG. 1 is a perspective view showing our new design for a mounting plate for a ski binding;

FIG. 2 is a top plan view thereof;

FIG. 3 is a right side elevational view thereof;

FIG. 4 is a bottom plan view thereof;

FIG. 5 is an enlarged perspective view of a first portion of our design;

FIG. 6 is an enlarged perspective view of a second portion of our design; and,

FIG. 7 is an enlarged perspective view of a third portion of our design.
